UNITED STATES PATENT OFFICE.

THOMAS PERRY WILLOUGHBY, OF BEAVERTON, OREGON.

DOOR-BUTT GAUGE.

Application filed October 20, 1925. Serial No. 63,670.

My invention relates to carpenters' tools and has for its object the marking of the location, width and depth of the butt to be placed upon the door and upon the jamb.

5 It is the usual custom to place two sets of butts upon each hinging, but I have provided means in my door butt gauge for the locating of two or more of the same to be done at one time and from one set up of the 10 device, to enable the user of the same to mark the door and the jamb. Each to be marked precisely as the other.

A further object of my invention, consists in a fabricated frame structure where- 15 in the same may be disassembled and placed in the ordinary carpenter's tool box and to not be of a greater length than the tools as ordinarily carried therein.

A further object of my invention, consists 20 in having blades placed therein which said blades may be renewed from time to time, or removed and sharpened and replaced within the marking heads.

A further object of my invention, con- 25 sists in the same being made of but few parts and of simple construction, and a door butt gauge that may be used by any ordinary workman not skilled in this kind of work.

30 With these and incidental objects in view, the invention consists in certain novel features of construction and combination of parts, the essential elements of which are set forth in the appended claims, and a pre- 35 ferred form of embodiment of which is hereinafter shown with reference to the drawings which accompany and form a part of this specification.

Fig. 1 is a partial cross section of a door 40 frame, illustrating my device in position therupon and in position for marking the width of the door butt or hinge to be placed thereupon.

Fig. 2 illustrates my new and improved 45 device in position for marking the depth of the butt or hinge upon the frame.

Fig. 3 illustrates my new and improved device for marking the width of the door butt or hinge upon the door.

50 Fig. 4 illustrates one of the heads for marking the depth of the same upon the door.

Fig. 5 is a perspective view of one of the heads in place upon the supporting frame.

55 Fig. 6 is an end view, taken on line 6—6 of Fig. 5, looking in the direction indicated.

Fig. 7 is an inverted plan view, partially in section of the marking head of the device.

Fig. 8 is a side elevation of the jointed frame, the same being in an enlarged view 60 of the upper or locating head of the same.

Like reference characters refer to like parts throughout the several views.

1 is the door casing, having a header 2, placed thereupon. My device is composed of 65 one or more sections, as shown at 3, the same being jointed together by any suitable telescopic fastening means, as shown at 4, and having disposed upon the upper end thereof an engaging stop 5, said stop being in adjustable relation with the frame member 3, and which may be locked to said frame member by suitable fastening means, as screws 6, the said screws being adapted to engage with the slot 7. The stop may be positioned and held in such position by a spring 8, adapted 70 to engage within the indentures 9, the object of which, is to provide the clearance between the underside of the header 2, and the top end of the door 28. The end 10 of the stop engages on the underside of the header 2, and the underside 11 of the stop, engages 75 on the upper side of the door 28. Where a standard space is to be provided, between the header 2, and the door 28, the same is gov- 80 erned by the depth 12 of the stop. If a greater, or a lesser distance is required between the header and the door, the same may be regulated by moving the stop relatively to the frame member, after the door casing has 85 been marked by the use of my device. I have described the stop 5 as being mounted to the upper section. In actual practice, either or both end sections are provided with a stop 90 5, though I have limited myself to the de- 95 scription of the stop upon one end of the sectional support. Located upon the jointed frame members 3, are a series of marking heads 13, which are in slidable relationship with the jointed frame members. The jointed frame members have graduated markings 14, thereupon, and a slot 15, longitudinally of the jointed frame, to maintain the marking heads in position and alignment thereupon. The marking heads in pairs are carried by an anvil head 16, and each head has 100 a graduated projection 17, projecting therefrom and slidably passing through the guide bars 18, which permits the marking heads to be moved laterally of the slotted rods 3, when 105 the guide bars are positioned on the rods 3 as shown in Fig. 5. The projections 17 may be

100

105

110

held in a stationary position by means of the screws 19 which are threaded through the top or head of the guide bars 18, and engage the projections 17. On the underside of the 5 guide bars 18 is another screw 19^a having the washer 19^b positioned thereon. The washer 19^b has a lesser width and a greater length than the width of the slot 15, and when the same is positioned with its length 10 transverse of the slot 15 it will maintain the guide bar 18 in sliding engagement with the bar 3, and by tightening the screw 19^a the guide bar 18 can be positioned in a stationary position on the bar 3. The anvil has 15 one fixed marking head 20, with the end marking blade 21 and side blade 21^a, disposed on the under side thereof. On the opposite end is a dovetail projection 22, and the marking head 23, with the end marking 20 blade 24 and side blade 24^a, secured thereto in slidable relationship with the dovetail projection 22, disposed on the under side of the anvil section. This marking head 23, may be adjustably positioned relative to the 25 stationary head 20 by suitable fastening means, as screw 25. By making the head 22 30 slidable relative to head 20, the exact length of the hinges may be marked by the end blades 21 and 24, by sliding the head 22 to or from the head 20; and of course the width 35 of the hinges may be marked by the blades 21^a and 24^a by positioning the projections 17 in the guide bars 18. The anvil 16, is made of substantial size and of material suitable 40 for receiving thereupon the blow of a hammer or mallet. When the marking heads have been positioned to mark the depth or 45 length and width of the door butt or hinge, and the device has been positioned upon the frame or door, a blow of the hammer or mallet of the workman upon the anvil section, causes a penetration of the anvil blades into the structure to be marked.

The locator wings 26 are pivotally disposed 50 upon each of the joints of the device, and when revolved in to operative position have outwardly extending arms 26^a which engage with the edge of the surface to be marked. These locator wings are used when the depth 55 of butt is to be marked, and this is particularly illustrated in Figs. 2 and 4.

In practice, the locator head, as shown in Fig. 8, is placed upon the under side of the header of the door frame, and the marking 60 heads are set to the width of the door butt or gauge, and the casing is marked as best illustrated in Fig. 1. The same is then set upon the door, as best illustrated in Fig. 3, and the width of the door butt or hinge, is 65 then marked upon the door. The instrument is then set for marking the depth of the door butt or hinge, as best illustrated in Fig. 2, and the same is marked by tapping the anvil member, to mark the depth upon the door 70 casing. The instrument is then transferred

to the door, as illustrated in Fig. 4, and the depth is then marked upon the door, after which the workman then removes the material and makes the door butt or hinge fast thereto.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. A door butt gauge, comprising an elongated sectional frame structure, marking heads in slidable relationship with the frame structure; means for maintaining the marking heads in fixed position relative to said frame; an end stop slidably disposed upon one end of said frame, adapted to engage with the head of a door frame and the upper edge of a door, to space the top of a door from said header; and marking blades disposed within the marking heads.

2. In a door butt gauge, an elongated sectional support member provided with longitudinal slots in each section; an anvil member movable longitudinally of said support member; a marking head formed on said anvil member; a second marking head supported by said anvil member and movable relative to the first mentioned marking head; each marking head being provided with support means slidably engaging the aforementioned slots; and incisive elements carried by each marking head.

3. A door butt gauge comprising an elongated sectional, graduated, fabricated frame structure; each section having guide slots disposed longitudinally thereof, marking heads slidably engaging with said guide slots, marking and cutter blades disposed within the marking heads, and means for positioning the gauge upon the jamb and upon the door in the same relative position.

4. In a door butt gauge, the combination of a frame composed of a plurality of elongated sections; there being a longitudinal slot formed in each section; guide bars slidably engaging said slots; means to maintain said guide bars in a stationary position along said slots; projections slidably disposed through said guide bars, means on said guide bars to position said projections; an anvil; a relatively stationary marking head and a relatively slidable marking head supporting said anvil; said marking heads each being supported by one of said projections; and means to secure the slidable marking head in a fixed position in relation to the stationary marking head.
